UNITED STATES PATENT OFFICE.

FRANK M. EDMONDS, OF HOLYOKE, MASSACHUSETTS, ASSIGNOR TO THE COBURN TROLLEY TRACK MANUFACTURING COMPANY, OF HOLYOKE, MASSACHUSETTS, A CORPORATION.

THERMAL DOOR-CLOSING DEVICE.

SPECIFICATION forming part of Letters Patent No. 738,714, dated September 8, 1903.

Application filed March 27, 1903. Serial No. 149,913. (No model.)

To all whom it may concern:

Be it known that I, FRANK M. EDMONDS, a citizen of the United States of America, residing at Holyoke, in the county of Hampden and State of Massachusetts, have invented new and useful Improvements in Thermal Door-Closing Devices, of which the following is a specification.

This invention relates to improvements in the construction of self-closing doors, and relates especially to devices applicable to the fire-doors held in an open position by means of devices associated with a piece of fusible metal which when ruptured permits the devices to operate to close the door, the object of this invention being to simplify the construction of the devices whereby the door is held open and whereby the same devices are rendered effective to close the door when the fusible metal is ruptured.

In the drawings forming part of this application, Figure 1 shows a portion of a door mounted upon an inclined track and having applied to it the devices which form the subject-matter of this application. Fig. 2 is an enlarged view, in side elevation, of the devices in the position they occupy when the door is held open prior to the rupture of the fusible member. Fig. 3 is a similar view showing the position of the parts after the rupture of the fusible element.

Referring to the drawings, *a* may indicate a wall having a door-opening therein over which and extending to one side of which opening is mounted an inclined track *b*, of any suitable type, on which the door *c* may be supported on rollers, as shown in Fig. 1 of the drawings, to the end that when not held in restraint the door may slide down the track *b* and close the opening in the wall.

Various devices have heretofore been used whereby the door may be held open by means of a weight, and associated with these devices a fusible strip of metal has been used, upon the rupture of which the devices assume a different position, and the same weight serves to close the door or to accelerate the closing movements thereof, which with these devices in another position holds the door open. A good example of constructions of this charac-

ter in present use is shown in the United States Letters Patent to Besse, No. 682,164, September 10, 1901. The construction therein shown, however, is imperfect, in that it does not provide for the free running of the door-restraining cord after the rupture of the fusible connection, and a further disadvantage consists in the fact that a part of the fusible strip may remain attached to the cord and possibly become entangled therewith in such a manner as to prevent the proper closing of the door at the critical moment. My invention overcomes these various defects and is carried into practice as follows:

Projecting beyond the forward edge of the door in a way to bring it well in front of the door-opening in the wall is a fixed arm *d*, on which is pivoted another arm *e*. The arm *d* is horizontal, while the arm *e* is slightly inclined from the vertical toward the end of the arm *d*, and between said arm *e* and the end of the arm *d* there is located a strip *f* of fusible metal, secured in any suitable way to each of said arms to hold them in fixed relation one to the other, so that the arm *e* may constitute a forwardly-inclined hook to receive the cord. Preferably a notch *g* is made in the forward edge of the arm *e*, near the upper end thereof, to receive the cord *h*, one end of which is fastened to the door at *i* and, passing around the end of the arm *e* in the notch *g*, runs back over a sheave or pulley *j* on the wall *a* and from thence downward, a weight being suspended on its lower end. The preferred manner is to carry the end of the cord *h* downward in a loop, as shown in Fig. 1, the weight *k* being provided with a pulley, through which the loop passes, as shown. Properly supported on the wall over the door is a bracket-arm *m*, which extends down alongside of the cord *h* just back of that part thereof which passes around the arm *e* and where, owing to the location of the supports of the cord, the latter doubles back upon itself in a vertical plane, which permits the location of a grooved pulley *o* on the arm *m* in such position that when the arm *e* swings backward and releases the cord *h* the latter will fall onto the grooved pulley *o*.

When the parts are in the position shown

in Figs. 1 and 2, the cord *h*, making, as it does, a short turn around the end of the arm *e*, is prevented from slipping thereon, and consequently the effect of the weight *k* is to hold 5 the door open; but as soon as the arm *e* is released and free to swing backward by the rupture of the fusible strip *f*, as shown in Fig. 3, the cord *h* will pass around the easily-rotatable pulley *o*, whereupon, free movement being 10 permitted to the cord, the effect of the weight *k* is transmitted to the lower portion of the cord, which is secured at the point *i* near the rear edge of the door. The weight therefore will operate to accelerate the closing 15 movement of the door.

From the foregoing description it is seen that the fusible strip *f* cannot in any way when ruptured be caught up by the cord and interfere with the freedom of movement of 20 the latter and that aside from this the cord has a perfectly-unobstructed straight run, not being doubled on itself or crossed at any point, and therefore the chances of fouling, whereby the door might at a critical time be 25 prevented from closing properly, are entirely avoided.

Having thus described my invention, what I claim, and desire to secure by Letters Patent of the United States, is—

30 1. The combination with a sliding door and an inclined track on which the door is mount-

ed, of a swinging arm supported on the door beyond the forward edge of the latter, and a strip of easily-fusible metal to retain said arm in a rigid position, a cord looped over the end 35 of said arm, a weight on the cord to hold the door open, one end of the cord being secured to the door near the rear edge thereof; a pulley not supported on the door, and located near said swinging arm, adapted to receive 40 the cord when the fusible strip is ruptured, and thereby reverse the action of the cord and weight, to effect the closing of the door.

2. The combination with a sliding door and an inclined track on which the door is supported, of a weight, a cord attached thereto by one end and having its other end attached to the door; suitably-supported pulleys over which the cord runs to effect the closing of the door by the weight; a swinging arm located near one of the pulleys and constituting a hook for the cord whereby, when the cord engages said arm, the action of the weight may be reversed to hold the door open, and a strip of fusible metal secured to said arm and 50 to a fixed abutment, to normally hold the arm rigid.
